FASTENER FOR SLIDING CLOSURES

Albert G. Dean, Narberth, Pa., assignor to The Budd Company, Philadelphia, Pa., a corporation of Pennsylvania

Application November 17, 1948, Serial No. 60,529

8 Claims. (Cl. 292—97)

1

This invention relates to a fastener for sliding closures and has for an object the provision of improvements in this art.

One of the particular objects of the invention is to provide an improved closure fastener which exerts a pulling action prior to locking in the closed position and which exerts a pushing action prior to releasing the closure for opening.

Another object is to provide a fastener which is operated by a single manual operating member or handle and which requires only one hand for operation.

Another object is to provide a fastener with a single manual operating element which moves in a natural manner and direction in both closing and opening actions to perform all of the required operations.

Another object is to provide a closure fastener which securely locks in the closed and pulled-up position.

Another object is to provide a closure fastener in which the manual operating element lifts the latch bar after pushing the door a short distance away from the frame and before releasing the door to open.

Another object is to provide a closure fastener with a latch bar which automatically rides over and engages its keeper; which cannot strike in such a way as to cause damage; and which lifts against the manual operating member when riding over its keeper in case the manual operating member has been pushed over to the closed and locked position.

The above and other objects and advantages of the invention will be apparent from the following description of an exemplary embodiment, reference being made to the accompanying drawings, wherein:

Figure 1 is an inside elevation of a sliding closure and its frame provided with a fastener embodying the present invention;

Figure 2 is an enlarged elevation of the fastener in the released position as the closure moves toward closed position;

Figure 3 is a view similar to Fig. 2 but showing the parts just as the door weatherstrip strikes the frame;

Figure 3a is a corresponding section through the weatherstrip, the section being taken on the line 3a—3a of Fig. 3;

Figure 4 is a view similar to Fig. 2 but showing the parts in the position in which the manual operating element is moved back to permit the latch to engage its keeper, in case the inertia of

2

the door has not caused the latch to engage the keeper;

Figure 5 is a view similar to Fig. 2 but showing the parts in fully closed position;

5 Figure 5a is a partial section taken on the line 5a—5a of Fig. 5;

Figure 6 is a view similar to Fig. 2 but showing the parts when the opening of the door is started;

10 Figure 6a is a corresponding section taken on the line 6a—6a of Fig. 6;

Figure 7 is a view similar to Fig. 2 but showing the parts when the latch has just begun to be lifted from its keeper;

15 Figure 7a is a corresponding section on the line 7a—7a of Fig. 7;

Figure 8 is a view similar to Fig. 2 but showing the latch in raised position and the door released for opening;

20 Figure 9 is a horizontal section taken on the line 9—9 of Fig. 1 to show the fastener in top plan view;

Figure 10 is a horizontal section taken on the line 10—10 of Fig. 5; and

25 Figure 11 is a vertical section taken on the line 11—11 of Fig. 4.

The closure fastener of the present invention is especially suitable for use on the sliding doors of railway mail and baggage cars which are subject to being frozen shut by ice in cold weather, and which normally are difficult to force open. The closure fastener hereby provided furnishes a strong initial opening force which breaks the ice seal so the door can be started to open. The fastener also provides a strong force for squeezing the door to its fully closed position where it is tight against its frame and upon its weatherstrip whereby to provide a tight weather seal. In serving these and its other functions, the fastener is easily manipulated by one hand.

30 40 The closure or door 10, as shown especially in Fig. 1, is mounted by roller hangers 11 to slide on an overhead supporting bar or rail 12 relative to its opening in the car wall to bring its front edge 13 toward the vertical side 14 of the door frame. A weatherstrip 15, which may be carried by either the door or the frame, here by the door, is squeezed between the door and frame in the closed position of the door.

45 The closure fastener, which is generally indicated by the reference numeral 20, is mounted on the door and its latch keeper pin 21 is mounted on the frame. A brace 22 braces the outer end of the pin 21 to the frame.

50 55 The fastener 20 is made as a self-contained unit with its moving parts carried between a rear

plate 24 and a front plate 25, the assembly being secured to the door by bolts 26 and the plates being spaced apart by sleeves 27 on the bolts. The operating parts of the fastener comprises a handle or manual operator 28 and a latch bar 29, the latch bar having a notch 30 in its lower edge adapted to engage the keeper pin 21.

The handle 28 is mounted by a pivot pin 32 to one or both of the plates 24, 25. It is shown as being mounted on the rear plate alone since clearance space, such as an aperture or slot, would need to be provided by the latch bar for the pin if it extended through to the front plate. With the closure confinement of the moving parts provided by the plates 24, 25, the single plate anchorage for the pin 32 is found sufficient to keep the parts in proper position and give adequate strength but the two-plate anchorage arrangement may be provided if found desirable.

The latch bar 29 is secured to the handle 28 by a pivot pin 33 and when not otherwise held up, the latch bar is adapted to rest with its lower edge on the sleeve 27 of the front bolt 26. The front end of the latch bar 29 is bevelled on the lower edge to provide a cam face 34 which is adapted to ride up on the keeper pin 21 when the door is closed. The parts are so arranged that in any position of the handle 28, the cam face 34 will engage the pin 21, if not held above it, whereby to avoid an end blow of the latch bar against the pin. To assist in easy movement of the cam face over the pin, the latter is provided with a loose roller sleeve 35.

On its upper edge, as shown in Fig. 6, the latch bar 29 is provided with a front abutment 36 and, as shown in Fig. 2, is also provided with a rear abutment 37, these abutments being adapted to be engaged in certain positions by means on the handle, such as the offset portion 38, by which the latch bar may be moved in certain ways by the handle. Specifically, as shown in Fig. 2, the handle holds the latch bar down when its offset portion 38 engages the front abutment 36; and, as shown in Fig. 7, raises the latch bar when the offset portion 38 engages the rear abutment 37. The abutments 36, 37 of the latch bar may be formed on opposite ends of a notch, and, as shown, the latch bar is widened at the rear end, as at 39, to properly locate the rear abutment 37 relative to the offset operating portion 38 of the handle. For the purpose of limiting the action of the offset portion 38 of the handle on the latch bar, the front plate 25 is provided with a front abutment 40 and a rear abutment 41, which abutments may be formed on opposite ends of a notch in the front plate 25. The rear plate 24, for convenience in manufacture is made with abutments like front plate 25, although in the present form the notches in the rear plate do not cooperate with the handle. In certain views where the front plate is left out for clarity, the abutments of the rear plate are referred to.

The operation of the fastener is shown in Figs. 2 to 8. In Fig. 2 the door is approaching the closed position and the cam face 34 of the latch bar has just begun to ride up on the keeper pin 21. Prior to engaging the keeper pin, the latch bar rested on the front mounting bolt 26. There are several positions in which the handle might be located when the door is being closed. It might be fully forward; it might be fully rearward; or it might be in any intermediate position. The fastener may be operated with the handle in any position. The most natural action is for the operator to pull the handle for-

ward as he pulls the door closed, and this is the position shown in Fig. 2.

As the door continues to close, the latch bar will continue to ride over its keeper pin to the position of Fig. 3 where the weatherstrip 15 just engages the door frame. Here several situations may develop depending on how the handle was held and how fast the door was closed. If the door is closed rapidly, it will compress the weatherstrip and at once allow the notch 30 of the latch bar to drop down over the keeper pin 21, as shown in Fig. 5. Either gravity or gravity assisted by handle pressure will cause the latch bar to drop down on its keeper.

If the latch bar does not engage its keeper pin in the first forward movement of the door, the handle may be manipulated, specifically being turned toward but not completely to the rear, to cause the latch bar to move forward and engage its keeper pin before the weatherstrip is compressed. Subsequent forward movement of the handle serves to pull the door tight by reaction upon the keeper pin to complete the closing movement of the door and thereby compress the weatherstrip. The start of this compressive closing action is shown in Fig. 4, wherein the dotted lines show the non-engaging position of the latch bar (the same as in Fig. 3) and the full lines show the retracted position of the handle and the corresponding pin-engaging position of the latch bar. Forward swinging movement of the handle from the full-line position of Fig. 4 to the position of Fig. 5 moves the shifting axis of the handle-latch pivot pin 33 around the fixed axis of the handle pivot pin 32 from the dotted position to the full line position of Fig. 5, thereby pulling the door tightly closed. It will be noted from Fig. 5 that in the fully closed position, the axis of pin 33 passes dead center position on a line joining keeper pin 21 and handle pivot pin 32, thereby locking the parts in drawn-up position. Here the handle offset 38 rests against the front plate abutment 40 to stop the forward movement.

The start of the opening action is shown in Fig. 6. Here the handle has been swung to the rear to move the pin 33 down and forward to push or cam the door back by reaction of the latch bar against the keeper pin. By a comparison of action centers and effective lever arms, it will be seen that the camming action to open the door, like the final closing action, is a very powerful one. Even a heavy ice seal can readily be broken by the door-opening action.

To continue with the door-opening action, Fig. 7 shows the handle offset 38 engaging the rear abutment 37 of the latch bar for lifting it, and Fig. 8 shows the parts after the latch bar has been lifted clear of its keeper pin. Here the handle offset 38 has engaged the rear abutment 41 of the front plate 25. Further rearward pushing action on the handle beyond this point serves to push the door open further.

It will now be evident that the invention provides a simple, strong and convenient fastener for sliding closures and one which may readily be manipulated by natural movements of one hand. It will also be evident that the invention may be variously embodied and modified in keeping with the present disclosure. And while the description places the fastener on a closure and the keeper on its frame, it will be evident that the location of parts may be reversed so far as applicable to such transposed use.

What is claimed is:

1. A fastener for a closure mounted to slide in a frame toward and from a keeper pin on the

frame, comprising in combination, a manual latch-operating member mounted on a pivot on the closure, a latch bar pivoted to said latch-operating member at one side of its own pivot, said latch bar having a cam-shaped end adapted to ride up on and over the keeper pin and having a notch adapted to drop down on and closely embrace the keeper pin on opposite sides when the closure is moved toward its closed position, means on the closure for holding the end of the latch bar up into position for its cam to engage and ride up on the keeper pin, the latch-operating member and latch bar pivots being so located that the latch bar pivot moves around the latch-operating member pivot and crosses a dead-center line passing through the keeper pin and the latch-operating member pivot when the latch-operating member is operated, whereby movement of the latch-operating member will give the latch bar a pull movement in passing to closed position and a push movement in passing to open position, and whereby the latch bar will be securely held in pulled-up position, and said latch-operating member and latch bar having interengaging elements by which the end of the latch bar is lifted up by the latch-operating member in moving to the open position and is urged down by the latch-operating member in moving to the closed position.

2. A fastener for a closure mounted to slide in a frame toward and from a keeper on the frame, comprising in combination, a manual latch-operating member pivoted on the closure, a latch bar pivoted to said latch-operating member at one side of its own pivot, said latch bar having keeper camming and engaging portions adapted to ride over and closely engage the keeper at opposite sides to provide a connection therewith to take a pull in closing and a push in opening, the latch-operating member and bar pivots being so located that the latch bar pivot moves around the latch-operating member pivot and crosses a dead-center line passing through the keeper pin and the latch-operating member pivot when the latch-operating member is operated, the latch-operating member and latch bar having interengaging elements by which the latch-operating member raises the latch bar in moving to the open position and urges the latch bar down in moving to the closed position.

3. A fastener for a closure mounted to slide in a frame toward and from one side of the frame which is provided with a keeper and a resilient sealing strip, said fastener comprising in combination, a latch-operating member pivoted on the closure, a latch bar pivoted to said latch-operating member on one side of its own pivot, said latch bar having elements adapted to cam over and closely engage the keeper on opposite sides to provide a connection therewith to take a pull in closing and a push in opening, the latch-operating member carrying the pivot of the latch bar in such manner that the latch bar pivot crosses a dead-center line passing through the keeper and the latch-operating member pivot when the latch-operating member is operated so as to pull the latch bar pivot in moving to closed position and a push movement in moving to open position, the latch-operating member and latch bar having elements which interengage toward opposite ends of the latch-operating member movement to lift the latch bar by interengagement of said interengaging elements on the latch-operating member and latch bar in moving to opening position, and to urge the latch bar down

in moving toward closed position, and whereby the parts are securely held in closed position, the movement of the latch bar along its length being greater than the movement of re-expansion in the resilient sealing means whereby in the closed position the sealing means is compressed and in the opening movement the parts are pulled free regardless of ice formation or the like at the sealed edge.

4. A fastener for a sliding closure adapted to cooperate with a keeper on the closure frame, comprising in combination, a latch bar carried by the closure on a movable pivot and having a releasable closely engaging connection with said keeper to take a pull in closing and a push in opening, and a latch-operating member associated with said latch bar and mounted on a pivot in such manner that movement of the latch-operating member causes the latch bar pivot to cross a dead-center line passing through the keeper and the latch-operating member pivot when the latch-operating member is operated so as to pull the latch bar pivot in moving to closed position and a push movement in moving to open position, and said latch-operating member having elements for engaging and moving said latch bar about its pivot in one or both extreme positions but the elements standing clear of the latch bar in intermediate positions.

5. A fastener for a sliding closure member having movement relative to a frame member and wherein a keeper is mounted on one member and the fastener is mounted on the other member, said fastener including a latch having a releasable closely engaging connection with said keeper to take a pull in closing and a push in opening, a latch-operating lever mounted on a fixed pivot and carrying a pivot for said latch in such position that the latch pivot moves across a dead-center line passing through said fixed pivot and keeper when the latch-operating lever is operated so as to produce a longitudinal force through the latch when the latch-operating lever is moved about its fixed pivot and to securely hold the parts in latched position against movement along the line of centers, the latch being gravity actuated to engage the keeper, means to limit the downward movement of the latch to a position where it is held up at a height to engage the keeper when the closure is moved toward it, and interengaging parts on said latch-operating lever and latch for moving the latch about its pivot by the latch-operating lever in certain positions near the end of the opening and closing movements.

6. A fastener for a sliding closure member having movement relative to a frame member and wherein a keeper is mounted on one of said members and a fastener is mounted on the other of said members, said fastener including a latch-operating arm mounted on a fixed pivot on said member, a latch pivoted to said latch-operating arm at one side of the fixed pivot, the latch being gravity actuated and so formed as to ride over and engage the keeper, means to support said latch in keeper-engaging position when the closure and frame members are moved toward each other, the latch pivot being movable across the dead-center line to cause the latch-operating arm to move the latch longitudinally in latching and releasing it and to securely hold it in latched position, abutment and abutment-engaging means between said latch-operating arm and latch at opposite ends of the latch-operating arm movement to cause said latch-operating arm to

move the latch up near one extreme position and to push it down near the other extreme position, and other abutment and abutment-engaging means between said latch-operating arm and fixed parts for stopping the movement of said latch-operating arm and thereby stopping the movement of the latch.

7. A fastener for a sliding closure member having movement relative to a frame member and wherein a keeper is mounted on one of said members and a fastener is mounted on the other of said members, said fastener including a latch-operating arm mounted on a fixed pivot on said frame member, a latch pivoted to said latch-operating arm at one side of the fixed pivot, the latch being gravity actuated and so formed as to ride over and engage the keeper, means to support said latch in keeper-engaging position, the latch pivot being movable across a dead-center line passing through said latch-operating arm pivot and keeper to cause the latch-operating arm to move the latch longitudinally in latching and releasing it and to move it across the dead-center line to securely hold it in latching position, abutment and abutment-engaging means between said latch-operating arm and latch at opposite ends of the latch-operating arm to cause said latch-operating arm to move the latch up near one extreme position and to push it down near the other extreme position, and other abutment and abutment-engaging means between said latch-operating arm and fixed parts for stopping the movement of said latch-operating arm and thereby stopping the movement of the latch, said latch-operating arm being mounted to extend above its fixed pivot and moving thereover between extreme positions whereby gravity acting on the latch-operating arm tends to hold the parts in either extreme position.

8. A fastener for sliding closures adapted to

cooperate with a keeper pin on a frame, comprising in combination, a latch-operating arm mounted on a fixed pivot on the closure, stop means between the latch-operating arm and parts on the closure for limiting the movement of the latch-operating arm in opposite extreme positions after free operating movement in an arc between the stop means, a latch pivoted to said latch-operating arm at one side of the fixed pivot in a position to cross a dead-center line passing through the keeper pin and fixed pivot when the latch-operating arm is operated, said latch having a notch adapted to closely embrace said keeper pin for a push and pull action thereagainst, abutment and abutment-engaging means between the latch-operating arm and latch providing limited free movement therebetween, the distance of free movement provided by the abutment and abutment-engaging means between the latch-operating arm and latch being less than that between the stop means for the latch-operating arm whereby the latch-operating arm moves the latch up or down about its pivot on the latch-operating arm near each extreme position, and means for holding the latch up to a position for engaging the keeper regardless of the position of the latch-operating arm, the latch pivot moving past the dead-center line into a position where the parts are securely held just before the latch-operating arm engages one of its stop means.
